UNITED STATES PATENT OFFICE.

JOHN T. STONEY, OF CLEVELAND, OHIO.

DEVICE FOR EXTRACTING CORE REINFORCING WIRES FROM CASTINGS.

Application filed January 31, 1927. Serial No. 164,993.

The present invention relates to a device for extracting core reenforcing wires from castings, particularly from castings such as engine cylinder blocks which have tortuous 5 interior openings or passages formed by sand core members shaped to conform to such passages.

Such sand core members are ordinarily quite fragile and must be handled with great 10 care in assembling the molds unless some means is provided for imparting strength and rigidity thereto. The core members may be made to possess sufficient strength for subsequent use by embedding therein 15 stiff reenforcing wires bent to conform to the shape of the core member and extending from end to end thereof. The main difficulty in employing such reenforcing wires is that the wires are exceedingly difficult to 20 remove from the casting, due to the fact that as they are withdrawn from the tortuous passage in the casting the wire must be progressively bent to conform to the passage as it is being withdrawn.

25 The present invention has for its object to provide a simple and effective means for quickly extracting core reenforcing wires from a casting.

30 A further object is to provide means for simultaneously pulling the core wires from opposite sides or ends of the casting so that it is not necessary to clamp the casting against movement while the wires are being extracted.

35 With the above and other objects in view, the invention may be said to comprise a device as illustrated in the accompanying drawings hereinafter described and particularly set forth in the appended claims, together with such variations and modifications thereof as will be apparent to one skilled in the art to which the invention appertains.

40 Reference should be had to the accompanying drawings forming a part of this specification in which:

Fig. 1 is a top plan view of the machine.

Fig. 2 is a rear elevation of the machine.

50 Fig. 3 is a side elevation of one of the wire reenforced core members.

Referring to the accompanying drawings the wire extracting mechanism is mounted upon an elongated supporting stand 1 which

is provided at the center thereof with a supporting portion 2 upon which the casting is 55 adapted to rest while the wires are being extracted. At the ends thereof the stand is provided with supporting portions 3 upon which are mounted longitudinally disposed fluid pressure cylinders 4 which are provided with pistons 5 to which are connected piston rods 6 which extend through the inner heads of the cylinders and have attached thereto heads 7 slidably mounted on longitudinal guide rods 8 which extend from the cylinder supporting portions 3 of the stand to adjacent the casting supporting portion 2. Each of the two heads 7 has a pair of axially aligned transversely disposed fluid pressure cylinders 9 mounted on opposite sides of the center thereof. Each of the cylinders 9 is provided with a piston 10 to which is attached a piston rod 11 extending through the inner head of the cylinder and having a wire gripping head 12 at its inner 75 end.

Fluid pressure cylinders 4 are controlled by a suitable controller 13 which operates the usual four-way valve to simultaneously admit pressure to the outer ends of the 80 cylinders and exhaust pressure from the inner ends thereof to simultaneously shift the heads 7 inwardly adjacent a casting on the supporting portion 2 or to supply pressure simultaneously to the inner ends of the cylinders 4 to shift the head 7 outwardly away from the casting. When the heads 7 are held adjacent the casting, the core reenforcing wires which project through openings at opposite sides or ends of the casting are positioned directly between the gripping heads 12 connected to the pistons of the cylinders 9 so that when the pistons 10 are actuated to move the heads 12 inwardly the wires projecting from each end of the casting are gripped between the heads 12 and will be stripped from the casting when the gripper supporting heads 7 are simultaneously moved away from the casting by the admission of pressure to the inner ends of the 90 cylinders 4.

In the operation of the machine the casting is placed upon the supporting portion 2 of the stand and the controller 13 is turned to a position to admit pressure to the outer 100 ends of the cylinders 4 causing the head 7

to be simultaneously moved inwardly and held at the end of the stroke adjacent the opposite ends of the casting. This positions the wire gripping heads 12 on opposite sides of the wires projecting through the openings at the ends of the casting and the controller 14 is turned to a position to admit pressure to the outer ends of the cylinders 9 causing the heads 12 to grip the wires between them. The controller 13 is then turned to the reverse position causing pressure to be exhausted from the outer ends of the cylinders 4 and admitting pressure to the inner ends thereof to simultaneously pull the gripper heads 7 outwardly away from the casting.

Chutes 15 are formed in the supporting stand 1 between the central supporting portion 2 and the end portions 3 thereof and when the heads 7 have been withdrawn a sufficient distance from the casting to free the wires therefrom the controller 14 is moved to reverse position causing the pistons 10 to move outwardly releasing the wires so that they fall into the chute 15 and are delivered to the rear side of the machine.

Sand chutes 16 may be provided beneath the central supporting portion 2 to catch sand discharged from the casting and these chutes may be provided with screen 17 which permit the sand to pass through them but prevent the passage of core reinforcing rods. The sand may be extracted from the interior of the castings while on the support 2 by means of a vibrator machine 18 provided with an arm 19 carrying the vibrating mechanism which is adapted to be swung into position over the casting and engaged therewith to shake the sand from the casting.

Having thus described my invention, what I claim is:

1. A device for extracting reenforcing wires from the core of a casting comprising a wire gripper, a support for the wire gripper, a support for the casting, means for moving one of said supports toward and from the other, and means for actuating said wire gripper.

2. A device for extracting reenforcing wires from the core of a casting comprising means for gripping said reenforcing wires, and means for causing a relative movement between the casting and gripping means to withdraw the wires from the casting.

3. A device for extracting reenforcing wires from the core of a casting comprising a support for a casting, a slide movable toward and from the said support, wire gripping means carried by the slide, means for actuating said slide, and means for actuating said wire gripping means.

4. A device for extracting reenforcing wires from the core of a casting comprising

a support for a casting, slides movable toward and from opposite sides of said support, wire grippers carried by each slide, means for simultaneously moving said slides, and means for simultaneously moving said wire grippers.

5. A device for extracting reenforcing wires from the core of a casting comprising a support for a casting, a fluid pressure cylinder, a member connected to the piston of said cylinder and movable toward and from a casting on the support, a pair of transversely disposed fluid pressure cylinders, and wire gripping members connected to the pistons of said cylinders.

6. A device for extracting reenforcing wires from the core of a casting comprising a supporting stand having a centrally disposed portion adapted to support a casting, fluid pressure cylinders mounted at opposite ends of said stand, a pair of heads slidably mounted on the stand between said cylinders, one connected to the piston of each cylinder, a pair of axially aligned transversely disposed fluid pressure cylinders on each head, wire gripping members connected to the pistons of said last mentioned cylinders, means for simultaneously actuating said longitudinally disposed cylinders, and means for simultaneously actuating said transversely disposed cylinders.

7. A device for extracting reenforcing wires from the core of a casting comprising a supporting stand having a centrally disposed portion adapted to support a casting, heads slidably mounted on the stand for movement into and out of engagement with the casting, means for simultaneously moving the heads into and out of engagement with the casting, and wire gripping means carried by said heads.

8. A device for extracting reenforcing wires from the core of a casting comprising means for supporting a casting, a member mounted for movement bodily toward and from said casting, wire gripping means on said member, means for moving said member toward and from the casting, and means for actuating said wire gripping means.

9. A device for extracting reenforcing wires from the core of a casting comprising means for supporting a casting, a pair of members mounted for movement bodily toward and from opposite sides of said casting, wire gripping means on each of said members, means for simultaneously moving said members toward and from the casting, and means for simultaneously actuating said wire gripping means.

10. A device for extracting reenforcing wires from the core of a casting comprising a support for a casting, a fluid pressure cylinder, a member connected to the piston of said cylinder and movable toward and from a casting on the support, wire

gripping means carried by said member, and means for actuating said gripping means.

11. A device for extracting reenforcing wires from the core of a casting comprising a support for a casting, a fluid pressure cylinder, a member connected to the piston of said cylinder and movable toward and

from a casting on the support, wire gripping means carried by said member, and fluid pressure operated means for actuating said gripping means.

In testimony whereof, I hereunto affix my signature.

JOHN T. STONEY.
